UNITED STATES PATENT OFFICE.

WILLIAM CRAIG, OF BROOKLYN, NEW YORK.

METHOD OF GETTING UP STEAM IN STEAM-BOILERS.

SPECIFICATION forming part of Letters Patent No. 327,659, dated October 6, 1885.

Application filed August 11, 1884. Serial No. 140,240. (No model.)

To all whom it may concern:

Be it known that I, WILLIAM CRAIG, of the city of Brooklyn, in the county of Kings and State of New York, have invented a new and 5 useful Method of Getting up Steam in Steam-Boilers, of which the following is a specification.

Modern marine boilers, more especially those of large size, are subjected to enormous 10 strains in getting up steam, by reason of the unequal expansion due to the wide variations in the temperature of the water in different parts of the boiler. In some marine boilers, if steam is got up quickly, it will be found that the temperature in the upper part of the boiler may 15 be over 320° Fahrenheit, while at the bottom of the boiler it may be as low as 50°. The differences in expansion commence as soon as the temperature in those parts of the boiler 20 which are most exposed to or affected by the heat of the furnace begins to rise, which is very soon after the fires are lighted, and continues many hours after the fires are lighted.

The object of my invention is to inaugurate 25 a new system of getting up steam in a steam-boiler, whereby the water may be raised to a high temperature which is uniform or nearly uniform throughout the boilers before fires are lighted in the furnace. By this system of 30 heating the water both the extent or degree and duration of the strain produced by unequal expansion will be reduced to a minimum.

The invention includes a method of getting 35 up steam in a main boiler, consisting in first getting up steam in another or supplemental boiler, in then simultaneously circulating and heating the water in the main boiler before the fires are lighted in the furnaces thereof by an injecting current of steam from the other 40 or supplemental boiler, and in starting the fires in the furnaces of the main boiler after the water therein has become so uniformly heated by steam from the other or supplemental boiler as to greatly lessen the liability 45 of strain due to unequal expansion by the heat of the fires in said furnaces.

The invention also includes a method of getting 50 up steam in a main boiler, consisting in first getting up steam in another or supplemental boiler, in then simultaneously circulat-

ing and heating the water in the main boiler before the fires are lighted in the furnaces thereof by an injecting current of steam from the other or supplemental boiler, whereby water is drawn from one part of the main boiler by the injecting current of steam, heated, and discharged into another part of the main boiler, and in starting the fires in the furnaces of the main boiler after the water has become so uniformly heated by steam from the other or supplemental boiler as to greatly lessen the liability of strain due to unequal expansion by the heat of the fires in the said furnaces. 55

By the method above described the water in a main marine boiler may be uniformly 60 heated to a temperature of 210° Fahrenheit (more or less) by means of steam taken from the donkey or supplemental boiler, and before the fires are lighted in the main boiler, and when there are a number of main boilers the water 65 in one of them may be thus heated with steam from the donkey-boiler before fires are lighted, and the steam generated in that main boiler 70 after the fires are lighted may be employed to heat the water in the other main boilers. 75

By this method of heating the water in the main boiler or boilers not only will the injurious effects of unequal expansion be greatly lessened, but a considerable saving of fuel 80 will be made over the ordinary method of heating the water in a boiler by fires in the furnaces thereof preparatory to making steam.

In carrying out my new method I may employ any of the means heretofore used for circulating the water in a steam-boiler after the 85 fires are lighted in the furnaces thereof; but I now deem it desirable to employ an injecting device arranged external to the main boiler, as shown in my United States Letters Patent No. 294,118, dated February 26, 1884, the suction-pipe of the injector or injecting device 90 leading from the lower or one part of the boiler and the discharge-pipe of the injector or injecting device leading to the upper or another part of the boiler. 95

In the accompanying drawings, Figure 1 is a perspective view illustrating a portion of a boiler and apparatus for carrying out my invention, also showing in dotted lines an arbitrary illustration of a donkey-boiler; and Fig. 100

2 is a sectional elevation of the rear end portion of a boiler with my apparatus applied thereto.

Similar letters of reference designate corresponding parts in both the figures.

A designates a main boiler, or one of a number of main boilers, constructed with internal furnaces. These furnaces are only shown in dotted outline, as the back end of the boiler is 10 illustrated; but the boiler may be constructed in any ordinary or approved manner.

I have represented the injecting device or injector B at the back of the boiler; but it may be arranged at the front or any other desired part thereof, and each boiler should be 15 provided with an injecting device or injector for producing a circulation of the water therein.

The injecting device or injector may be of 20 any well-known or suitable type, and is provided with supply and discharge pipes C D, whereby it is connected with different parts of the boiler. As here shown, the supply-pipe C leads from a point very near the bottom of 25 the boiler to the water-inlet of the injector B, and the discharge-pipe D leads from the injector to the upper part of the boiler, and may enter the boiler at a point near the water-line.

Steam is supplied to the injector B through 30 a pipe, E, in which is a valve, E', and communication of the supply and delivery pipes with the boiler is controlled by valves C' D'. The injector may also be provided with the usual overflow, S.

35 The supply-pipe C has a branch, C², extending below its point of connection with the boiler, and provided with a valve, C³. From the discharge-pipe leads a branch pipe, D², provided with a valve, D³. The branches C² 40 D², with their valves, serve a purpose herein-after described.

As here represented, the steam-supply pipe E is connected with the steam-space of the boiler A, and from it extends a branch steam-pipe, E*, which I have shown partly in dotted lines, and which leads from an arbitrary representation of a donkey-boiler, F, also shown in dotted lines. In the branch steam-pipe E* is a valve, a, and in the main steam-pipe E, between the branch pipe E* and the boiler A, is a valve, E².

When the time has arrived for heating the water in the boiler A, and before the fires are lighted therein, the valves C' D' are opened to 55 place the injector in communication with the water in the boiler, and the valves E' a are then opened to admit steam from the donkey-boiler to the injector. By the current of steam thus passed through the injector the water is taken from the bottom of the boiler A, heated, and delivered into the top thereof, and the impelling current of steam becoming mingled with and condensed by the water im-parts heat thereto, thereby heating and cir- 60 culating the water simultaneously.

65 It will be understood that this heating of

the water in the boiler A is performed before the fires in the furnaces thereof are lighted, and the heating is continued until the water has a nearly-uniform temperature throughout, and is almost or quite hot enough to generate vapor. When the water in the boiler A has thus been uniformly heated by the mingling of steam with it, the fires in the furnaces are lighted, and the circulation of water by the 70 injector may be continued with steam from the donkey-boiler F until steam is generated in the main boiler, and may be thereafter continued with steam from the boiler A, the valve a being closed and the valve E² opened. When 80 this method is carried out, the water in the boiler is thus heated uniformly, or nearly so, throughout before the fires therein are lighted, and the evil effects of unequal expansion are to a great extent obviated, and not only is 85 this most desirable result attained, but less coal will be used than is required when the preliminary heating of the water is performed by fires in the furnaces.

When there are two or more main boilers, the 90 water in one of them may be thus heated by steam from the donkey-boiler before the fires are lighted in the furnaces, and after steam is generated in that main boiler by fires in the furnaces the water in the other boiler or boilers 95 may be thus heated by steam from the first main boiler.

It is obvious that to secure a uniform heating of the water in the boiler A the water may with advantage be drawn through the supply-pipe C from different points along the length of the boiler, and may be widely distributed from the delivery or discharge pipe D. To provide for this, the said supply and discharge pipes C D may have perforated prolongations 100 C² D² extending within the boiler, as shown in Fig. 2. These prolongations may be extended nearly the entire length of the boiler, if desired, and should be closed at the ends to compel the water to pass through the perforations.

It may be desired to use the injecting device B for discharging the water from the boiler A when steam is off. In such case it is only necessary to close the valve D' in the discharge-pipe D and open the valve D³ in the branch pipe D². The water taken from the bottom of the boiler may then be discharged overboard by steam from the donkey-boiler.

It may also be desirable to employ the injector to discharge bilge-water, and if so the valve D³ is still left open, and the valve C³ in the branch suction or supply pipe C² is also opened, the valve C' being closed. When each of the main boilers of a vessel is provided with an injector thus arranged, they may all be operated by steam from their respective boilers to clear the vessel of water in case of accident.

Although I have shown the supply-pipe as 130 arranged to take water from the bottom of the boiler and the discharge-pipe as arranged to

deliver water into the upper part of the boiler, they might be otherwise arranged to take water from any part of the boiler and deliver it to another part thereof, as may be most desirable.

The holes in the pipes that extend throughout the top and bottom of the boiler should be laid out differentially—that is to say, a small number in the first twelve inches of their length and increasing in numbers as to their length—for the purpose of drawing and discharging the water uniformly throughout the length of the boiler.

I am aware that to enable steam to be generated in a locomotive more rapidly than heretofore after the fires are lighted it has been proposed to introduce steam from another or supplemental boiler simultaneously into the steam space or dome and flue or smoke-stack of the locomotive. The steam which is introduced into the steam space or dome serves to heat the water, and the steam which is introduced into the flue or smoke-stack serves to create a draft, which promotes combustion in the furnace of the locomotive.

I am also aware that to promote the draft when fires are first lighted in locomotives, and to facilitate the heating of the water therein, it has been proposed to discharge steam from a supplemental boiler simultaneously into the smoke-stack and water-space of a locomotive. The purpose of discharging steam into the smoke-stack is to promote a draft in the locomotive while stationary, and just after starting a fire in the furnace thereof, and the purpose of introducing steam into the water-space of the locomotive is to heat the water on the inside of the boiler-plates at the same time they are heated on the outside by the furnace-fire.

In both the above-described methods no steam is discharged into the locomotive-boiler until after the fires are lighted therein, and in this respect both said methods differ from that pursued by me. In carrying out my improved method I produce by an injecting current of steam from a supplemental boiler a rapid circulation of the water in the main boiler before the fires are lighted in the fur-

nace thereof, and I do not light said fires until all the water in the main boiler has been brought to a uniformly highly-heated state by the circulation produced by the injecting current of steam from the supplemental boiler.

I do not desire to include in my invention any method which involves the lighting of the fires in the furnace of the main boiler first and the injecting of steam into the water of the main boiler afterward.

What I claim as my invention, and desire to secure by Letters Patent, is—

1. The herein-described method of getting up steam in a steam-boiler, consisting in first getting up steam in another or supplemental boiler, in then simultaneously circulating and heating the water in the main boiler before the fires are lighted in the furnaces thereof by an injecting current of steam from the other or supplemental boiler, and in starting the fires in the furnaces of the main boiler after the water therein has become so uniformly heated by steam from the other or supplemental boiler as to greatly lessen the liability of strain due to unequal expansion by the heat of the fires in said furnaces, substantially as herein set forth.

2. The herein-described method of getting up steam in a main boiler, consisting in first getting up steam in another or supplemental boiler, in then simultaneously circulating and heating the water in the main boiler before the fires are lighted in the furnaces thereof by an injecting current of steam from the other or supplemental boiler, whereby water is drawn from one part of the main boiler, heated, and discharged into another part thereof, and in starting the fires in the furnaces of the main boiler after the water therein has become so uniformly heated by steam from the other or supplemental boiler as to greatly lessen the liability of strain due to unequal expansion by the heat of the fires in said furnaces, substantially as herein set forth.

WILLIAM CRAIG.
